Patented Oct. 16, 1917.

FIG. 1.

UNITED STATES PATENT OFFICE.

BERTHA HALLETT BOHANNON, OF DAYTONA, FLORIDA.

CHILD'S ONE-BUTTON ROMPER.

1,243,583

Specification of Letters Patent. Patented Oct. 16, 1917.

Application filed August 7, 1916. Serial No. 113,631.

To all whom it may concern:

Be it known that I, BERTHA H. BOHANNON, a citizen of the United States, residing at Daytona, Volusia county, Florida, have invented a certain new and useful Child's One-Button Romper; and I hereby declare that the following is a full, clear, and exact description thereof, reference being had to the accompanying drawing, which forms part of this specification.

This invention is a novel romper or overall for small children. Its object is to provide a romper which can be very quickly put on or removed from the child; will require but one button or fastener to secure it; will be very simple in construction, neat in appearance, economical in material required, and comfortable to the wearer.

I will explain the invention with reference to the accompanying drawings in which:

Figure 1 is a front view of the complete garment.

Fig. 2 is a back view thereof.

Fig. 3 is a section on line 3—3 Fig. 1.

Fig. 4 is an enlarged detail section on line 4—4 Fig. 2.

The garment comprises a front section 1 and two rear sections 2 and 3 which are substantially similar but reversed.

The front section 1 has leg portions, 1^a, 1^b, and arm portions 1^c, 1^d; these leg and arm portions may be of any desired length, but are preferably short, as indicated. The front section also has a neck opening or notch 1^e.

The left-hand back section 2 is provided with a leg portion 2^a, and arm portion 2^c. The leg portion 2^a is complementary to the adjacent leg portion 1^a of section 1; and the arm portion 2^c is complementary to the adjacent arm portion 1^c of section 1.

Section 2 extends beyond the center line of the section 1, and has alapping portion 2^b that is connected at bottom adjacent the crotch to the adjacent edge of the leg portion 1^b of section 1 as shown at 2^b, and which extends upwardly and merges into a belt strap 2^d; thelapping portion 2^b also extends from the belt strap 2^d to the neck 2^e as indicated in Figs. 1 and 2.

The section 2 may be sewed to section 1 by a shoulder seam 1^f, side seam 1^g, and a

crotch seam 1^h, and side seam 1ⁱ also continuing under the arm 2^c as indicated at 1^j. 55

The right-hand back section 3 is preferably similar to but the reverse of section 2; and has a leg portion 3^b, complementary to the leg portion 1^b of section 1; and an arm member 3^d complementary to the arm member 1^d of section 1. It also has alapping portion 3^e, and neck portion 3^f which merge into the belt strap 3^g.

Section 3 is united to section 1 by a shoulder seam 3ⁱ and side seams 3^j, and it is 65 united at the crotch seam 1^h to both the sections 1 and 2 as shown.

The depth or width of the crotch or recess between the opposite leg portions of the garment may be varied according to the width 70 and fullness it is desired the romper shall have at this point.

The belt or straps 2^d and 3^g are made of such length that when the garment is placed on the child the ends of these belts may be 75 fastened together at the front as indicated in Fig. 1. The belt straps may be secured by a button 4 or other fastening of any suitable kind.

The belt strap 2^d may be passed through 80 an opening 3^m in the romper to bring it outside the garment; such opening can be conveniently made by leaving a slit in the seam 3^j at the proper point.

It will be seen that this garment provides 85 a neat simple practical one-piece romper with a one-button fastening. The legs are securely united at the crotch, yet the romper is sufficiently roomy at the crotch to make it entirely free and comfortable to the child 90 and does not encumber its movements. When upon the child the romper presents a very neat appearance; and the romper may be placed over other clothing to protect the latter. The romper does not interfere 95 with the free movements of the child, nor bind it in any way, and at the crotch, which is usually the weakest point, it is strengthened by the overlapping of the portions of the sections 2 and 3, and the seam 100 uniting these sections at the crotch reinforces and strengthens the romper at what is usually its weakest point. The overlapping also precludes any possibility of a gaping apart at that section.

The romper can be readily put on or taken 105

off the child by the parent or nurse; yet is securely fastened when on the child by a single fastener.

What I claim is:

- 5 A romper having an integral front body section having sleeve portions and short leg portions, a back portion comprising two sections each attached to the front section at the adjacent side and shoulder thereof and com-

pleting the sleeves and legs, said back sections being provided with belt straps adapted to extend around the waist, and the back sections overlapping each other a substantial distance at the back and crotch, and a line of stitching joining the overlapped back sections and the front section at said crotch.

BERTHA HALLETT BOHANNON.
